10 Claims

ABSTRACT OF THE DISCLOSURE

Dihydronorthebainone and dihydronororipavine compounds and the corresponding enol lower alkyl ethers which have an unsaturated group or a cycloalkylmethyl group as an N-substituent are prepared by reduction of the corresponding dihydronorthebaines or dihydronorripavines or by N-substitution of the corresponding N-unsubstituted dihydronorthebainone or dihydronorripavine compounds or the enol lower alkyl ethers. These compounds have analgesic activity.

This invention relates to new thebaine and oripavine derivatives having pharmacological activity. More specifically the compounds of this invention have analgesic activity as demonstrated in standard animal pharmacological test procedures. For example, in the hot plate test, analgesic activity is produced in mice at doses of 5 to 15 mg./kg. subcutaneously. Also, the compounds of this invention are active as morphine antagonists in the hot plate test at doses of from 1 to 100 mg./kg. subcutaneously in mice.

The compounds of this invention are represented by the following general formula:

Formula I

in which:

R₁ is

in which R₅, R₆ and R₇ are hydrogen, methyl or halogen, for example allyl, 2,3-dichloroallyl or 3,3-dimethylallyl; propargyl or cycloalkylmethyl such as cyclopropylmethyl, cyclobutylmethyl, cyclopentylmethyl or cyclohexylmethyl;

R₂ is hydrogen, lower alkyl preferably methyl, acyl such as a lower alkanoyl (for example acetyl, propionyl, butyryl or isobutyryl), benzoyl, nicotinoyl or isonicotinoyl;

R₃ is hydrogen or acyl such as lower alkanoyl; and R₄ is hydrogen or lower alkyl, preferably methyl.

Preferred compounds of this invention are represented by Formula I when:

2

R₁ is

5 in which R₅, R₆ and R₇ are hydrogen, methyl or chloro or cycloalkylmethyl, preferably cyclopropylmethyl or cyclobutylmethyl;
R₂ is hydrogen or methyl;
R₃ is hydrogen or lower alkanoyl; and R₄ is methyl.

10 Exemplary of advantageous compounds of this invention are N - cyclopropylmethyl- Δ^5 -dihydronorthebainone enol methyl ether, N - cyclopropylmethyl - Δ^5 -dihydronororipavine enol methyl ether, N - cyclobutylmethyl - Δ^5 - dihydronorthebainone enol methyl ether, N-3,3-dimethylallyl- Δ^5 -dihydronorthebainone enol methyl ether and N-allyl- Δ^5 -dihydronorthebainone enol methyl ether and the pharmaceutically acceptable acid addition salts thereof.

15 The terms "lower alkyl" and "lower alkanoyl" are used herein as meaning groups containing from 1 to 4 carbon atoms inclusive.

20 Although included within the scope of the invention are the pharmaceutically acceptable acid addition salts of the compounds of Formula I.

25 It will be appreciated by those skilled in the art that in those compounds of Formula I in which R₄ is hydrogen keto-enol tautomerism is possible. In such compounds the keto form is believed to be predominant.

The compounds of Formula I in which R₃ is hydrogen may be prepared either (a) by hydrogenation (reduction) of a compound of the general formula:

Formula II

30 in which R₁ and R₄ have the same meanings as in Formula I and R₂ is hydrogen or lower alkyl, the hydrogenation being effected under conditions such that only the heterocyclic oxygen atom is affected and not any unsaturated group which may be present as R₁, for example using metallic sodium in liquid ammonia, or (b) by N-substitution of a compound of the general formula:

Formula III

35 in which R₄ has the same meaning as in Formula I and R₂ is hydrogen or lower alkyl, with a reactant which will give the desired R₁ substituent on the nitrogen atom, for example R₁-X in which X is halide.

40 The compounds of Formula III, which are also objects of this invention, may be obtained by the method (a) described above, R₁ being hydrogen.

45 The compounds of Formulas II and III may be prepared from the known starting compounds dihydromorphinone, dihydronormorphinone, dihydrocodeinone or dihydronorcodeinone by suitable synthetic routes. 50 Procedures for preparing the starting materials of Formula II and some of these compounds are described in U.S. Patent 3,299,072.

The compounds of Formula I in which R₂ and/or R₃ are acyl are prepared by acylation of the corresponding compounds in which R₂ and/or R₃ are hydrogen, using for example the appropriate equivalent amount of an acyl halide or acid anhydride generally in the presence of an acid binding agent, for example pyridine and, where appropriate, separating acylated products by fractional crystallization and/or chromatography.

The compounds of Formula I in which R₄ is hydrogen may also be prepared from the corresponding compounds of Formula I in which R₄ is a lower alkyl group by acid hydrolysis using, for example, hydrobromic acid.

The pharmaceutically acceptable acid addition salts of the compounds of Formula I may be prepared by reacting the base with an acid which will give the required salt, for example by treating the base in an organic solvent with an equivalent amount of the desired acid.

At the present time the position of the double bond in the non-aromatic unsaturated ring of the compounds of Formulas I, II and III are not known for certain, although in the compounds of Formulas I and III it is thought to be in the C₅-C₆ position while in the compounds of Formula II it is thought to be in the C₆-C₇ position. However for the sake of simplicity in describing the present invention it will be assumed that the double bond is in position 5,6 in the compounds of Formulas I and III and in the position 6,7 in the compounds of Formula II.

It will be appreciated that for therapeutic use the compounds of the invention will generally be administered as a pharmaceutical composition comprising a compound of the invention as an essential active ingredient in association with a pharmaceutical carrier of a kind normally employed in the production of drugs ready for administration. Advantageously the composition is made up in a dosage unit form suitable for the desired mode of administration. Thus for oral administration the dosage unit may be, for example, a tablet, capsule, pill or troche, while for parenteral administration the dosage unit may be, for example, an ampule or the like container having disposed therein an injectable substantially isotonic saline solution of the active compound in pyrogen free distilled water.

The following examples illustrate the invention and are not intended to restrict the scope thereof.

EXAMPLE 1

N-cyclopropylmethyl- Δ^6 -dihydroronthebaine (1.5 g.), obtained in the manner described in Example 3 of U.S. 3,299,072, is dissolved in dry tetrahydrofuran (30 ml.) in a 250 ml. flask fitted with a reflux condenser cooled by solid carbon dioxide and the flask is cooled to -80° C. with a bath of solid carbon dioxide/acetone. Liquid ammonia (90 ml.) is then added to the resulting solution by distillation into it. The temperature of the resulting reaction mixture is then allowed to rise until the ammonia refluxes gently. Metallic sodium is then added in small (about 50 mg.) pieces as soon as the previous piece has dissolved. When the reaction mixture becomes permanently blue, which occurs when 0.5 g. of sodium has been added, ammonium chloride (1 g.) is added, the reflux condenser is removed and the ammonia is allowed to evaporate at room temperature. To the remaining reaction mixture (a milky fluid) are added water (30 ml.) and brine (saturated sodium chloride solution, 100 ml.) and the mixture is then extracted with benzene (50 ml.). The separated benzene solution is dried with anhydrous magnesium sulphate, filtered and evaporated under reduced pressure leaving a white foam. On adding diethyl ether to the foam, N-cyclopropylmethyl- Δ^6 -dihydroronthebaine enol methyl ether is obtained in colorless needle clusters having a M.P. of 95-96° C.

A portion (1 g.) of this product is dissolved in dry diethyl ether (10 ml.) and a saturated solution of salicylic acid in dry diethyl ether is added dropwise until no further precipitation occurs. The solid is separated by

filtration and recrystallized from 95% ethanol (rectified spirit) to give the salicylate salt as large colorless prisms having a M.P. of 164.5-165.5° C.

EXAMPLE 2

N-cyclopropylmethyl- Δ^6 -dihydroronripavine (2.2 g.), obtained in the manner described in Example 5 of U.S. 3,299,072, is dissolved in dry tetrahydrofuran (30 ml.) following which the procedure described in the foregoing Example 1 is followed. The total quantity of sodium required is 0.48 g. and when the ammonia has evaporated a brown solution remains which is extracted as described in Example 1 so as to obtain N-cyclopropylmethyl- Δ^6 -dihydroronripavine enol methyl ether.

A sample of the above prepared product (1.4 g.) is added to one equivalent of salicylic acid dissolved in the minimum quantity of ethanol and warmed to 50° C. until a clear solution is obtained. On standing, a crystalline product forms which is filtered off and recrystallized from ethanol to give the salicylate salt of N-cyclopropylmethyl- Δ^6 -dihydroronripavine enol methyl ether as cream colored needles having a M.P. of 206-208° C. (decomp.).

EXAMPLE 3

N-cyclobutylmethyl- Δ^6 -dihydroronthebaine (3 g.) is dissolved in dry tetrahydrofuran (30 ml.) in a flask fitted with a reflux condenser cooled by solid carbon dioxide. The resulting solution was stirred in a bath of solid carbon dioxide/acetone at -80° C. under dry nitrogen. Liquid ammonia (90 ml.) is then distilled into the solution. The carbon dioxide/acetone bath is removed and the ammonia is allowed to reflux gently. Metallic sodium (1.0 g.) is then added portionwise in 50 mg. pieces until the reaction mixture becomes permanently blue. Solid ammonium chloride (1 g.) is added with the result that the reaction mixture becomes colorless. The ammonia is then evaporated and to the remaining reaction mixture are added saturated sodium chloride solution (50 ml.) and water (50 ml.). The resulting mixture is then extracted with benzene and the benzene extracts are dried over anhydrous magnesium sulphate, filtered and then evaporated to give a colorless glass-like solid. On dissolving this glass-like solid in ether, colorless needles of N-cyclobutylmethyl- Δ^6 -dihydroronthebaine enol methyl ether are deposited, M.P. 104-105° C.

The N-cyclobutylmethyl- Δ^6 -dihydroronthebaine starting material is prepared in the following manner:

Stage 1.—Dihydroroncodeinone (15 g.) is dissolved in dioxane (150 ml.) and water (15 ml.) and anhydrous potassium carbonate (15 g.) added. The resulting mixture is stirred and cyclobutyl carbonyl chloride (10.5 g.) is added dropwise during 30 minutes. Stirring is continued for a further three hours and the reaction mixture is then poured into water (500 ml.) and the resulting suspension adjusted to a pH of 11.0 by addition of 2 N sodium hydroxide solution. This suspension is then extracted with chloroform (1× 200 ml.+2× 100 ml.) and the combined chloroform extracts are successively washed with N hydrochloric acid (150 ml.) and water (100 ml.) and then dried over anhydrous magnesium sulphate. Filtration and evaporation of the filtrate under reduced pressure gives N-cyclobutylcarbonyldihydroroncodeinone as a white foam.

Stage 2.—Metallic sodium (0.855 g.) is added to a mixture of dry tertiary butyl alcohol (152 ml.) and dry methanol (1 ml.) and the mixture heated in an atmosphere of dry nitrogen until solution of the metal is complete. After cooling to room temperature a further quantity of tertiary butyl alcohol (76 ml.) is added and stirred (still in dry nitrogen atmosphere) while N-cyclobutylcarbonyldihydroroncodeinone (11.79 g.), dissolved in dry tertiary butyl alcohol (130 ml.), is added in a steady stream resulting in a clear yellow solution. To this solution is added a solution of dimethyl sulphate (4.3 g.) in dry tertiary butyl alcohol (25 ml.) dropwise and with

stirring during one hour and the resulting mixture is then heated to refluxing temperature for a further two hours.

The solvent is then removed under reduced pressure and the residue is stirred for 15 minutes with dilute aqueous ammonia (20 ml. of "0.880" ammonia diluted to 500 ml. with water) and then extracted with benzene (2X 150 ml.+1X 100 ml.). The combined benzene extracts are washed with water (100 ml.), dried with anhydrous magnesium sulphate, filtered and evaporated under reduced pressure to dryness. The residue is redissolved in dry benzene and chromatographed on activated alumina, type H (150 g.). Elution with benzene and evaporation of the eluate under reduced pressure gives a white foam which crystallizes on addition of a little diethyl ether and has a M.P. of 140-141° C. This material is N-cyclobutylcarbonyl- Δ^6 -dihydroronthebaine.

Stage 3.—To a suspension of lithium aluminium hydride (2.5 g.) in dry tetrahydrofuran (100 ml.) is added a solution of the above N-cyclobutylcarbonyl- Δ^6 -dihydroronthebaine (5 g.) in dry tetrahydrofuran (125 ml.). The mixture is heated to reflux for three hours in an atmosphere of dry nitrogen and then cooled to 0° C. and the residual complex and excess lithium aluminium hydride is decomposed by the dropwise addition of a mixture of tetrahydrofuran (20 ml.) and water (2.5 ml.) followed by 15% sodium hydroxide (2.5 ml.) and water (7.5 ml.) in that order. The precipitate is filtered off and washed with diethyl ether (200 ml.). The filtrate and washings are combined, dried with anhydrous magnesium sulphate, filtered and evaporated under reduced pressure. The residue is a colorless gum which is dissolved in a minimum quantity of warm diethyl ether and on standing forms a crystalline precipitate of N-cyclobutylmethyl- Δ^6 -dihydroronthebaine, M.P. 135-137° C.

EXAMPLE 4

N-3,3-dimethylallyl- Δ^6 -dihydroronthebaine (4.96 g.) is reduced with metallic sodium in liquid ammonia in a manner similar to that described in Example 1 to give N-3,3-dimethylallyl- Δ^6 -dihydroronthebainone enol methyl ether as small colorless needles of M.P. 119-120° C.

The N-3,3-dimethylallyl- Δ^6 -dihydroronthebaine starting material is prepared in the following manner:

Stage 1.—A mixture of dihydronorcodeinone (12.15 g.), 1-bromo-3-methyl-2-butene (6.7 g.), sodium bicarbonate (5.37 g.) and N,N-dimethylformamide (110 ml.) is stirred at refluxing temperature for five hours. The reaction mixture is then cooled to room temperature and filtered; the residual solid on the filter is washed with ethanol. The combined filtrate and washings are evaporated under reduced pressure leaving a residue of a dark brown oil. This oil is dissolved in 2 N hydrochloric acid (100 ml.) and the solution washed with diethyl ether (3X 100 ml.). The aqueous phase is then made strongly alkaline by the addition of "0.880" ammonia solution and extracted with diethyl ether (3X 100 ml.). The combined ethereal extracts are dried over anhydrous magnesium sulphate and evaporated giving crude N-3,3-dimethylallyl-dihydroroncodeinone (11.88 g.) as a brown glassy solid. This is purified by dissolving in ethanol (75 ml.) and adding the resulting solution dropwise with shaking to a solution of (+) tartaric acid (5.1 g.) in ethanol (50 ml.). On standing, cream colored needles (16.7 g.) of M.P. 119-120° C. separate and are filtered off. These are dissolved in a minimum of cold water and the solution basified with "0.880" ammonia solution when a yellow sticky solid separates which is then extracted with diethyl ether (3X 100 ml.). The combined ethereal extracts are dried with anhydrous magnesium sulphate, filtered and evaporated under reduced pressure giving pure N-3,3-dimethylallyl-dihydroroncodeinone as a colorless foam.

Stage 2.—The compound (10 g.) prepared in Stage 1 is methylated in exactly the manner described in Example 3, Stage 2 to provide N-3,3-dimethylallyl- Δ^6 -dihydroronthebaine as a colorless foam.

EXAMPLE 5

N-allyl- Δ^6 -dihydroronthebaine (1.04 g.), obtained in the manner described in Example 11 of U.S. 3,299,072, is reduced by metallic sodium in liquid ammonia in the manner described in Example 1 to give N-allyl- Δ^5 -dihydroronthebainone enol methyl ether as a colorless foam.

This free base is converted into its salicylate salt by dissolving it in dry diethyl ether (10 ml.) and adding to the solution so formed a solution of salicylic acid (0.49 g.) in diethyl ether (10 ml.) to form a white solid precipitate, which is filtered off and recrystallized from an ethanol/water mixture to give colorless rhombic rods of N-allyl- Δ^5 -dihydroronthebainone enol methyl ether salicylate, M.P. 142-143° C.

EXAMPLE 6

N-allyl- Δ^5 -dihydroronthebainone enol methyl ether (1.4 g.), prepared in the manner described in Example 5, is dissolved in ethanol (10 ml.) and 3.7 N hydrobromic acid (1.14 ml.) is added, the resulting mixture then being heated for one hour at 50-60° C. Evaporation of the solvent under reduced pressure gives a yellowish brown solid which is then recrystallized from ethanol to give N-allyl-dihydroronthebainone hydrobromide as buff colored rods, M.P. 234-236° C.

EXAMPLE 7

N-cyclopropylmethyl- Δ^5 -dihydroronthebainone enol methyl ether (1.0 g.), prepared in the manner described in Example 1, is mixed with acetic anhydride (1.0 ml.) and dry pyridine (5 ml.) and the resulting mixture is stirred for 20 hours at room temperature and then poured into water (10 ml.). Saturated aqueous sodium bicarbonate solution (40 ml.) is added and the resulting mixture is extracted with diethyl ether (3X 50 ml.). The combined ethereal extracts are dried with anhydrous magnesium sulphate, filtered and evaporated under reduced pressure leaving a residue of a colorless foam (1.0 g.). The foam is dissolved in diethyl ether (20 ml.) and a solution of salicylic acid (0.35 g.) in diethyl ether (20 ml.) is added. A white solid precipitates which is filtered off and recrystallized from an ethanol/water mixture to give colorless rhombic rods of O-acetyl-N-cyclopropylmethyl- Δ^5 -dihydroronthebainone enol methyl ether, M.P. 160-161° C.

Similarly, using propionyl chloride, butyryl chloride and isobutyryl chloride in the above procedure, the products are, respectively, O-propionyl-N-cyclopropylmethyl- Δ^5 -dihydroronthebainone enol methyl ether, O-butyryl-N-cyclopropylmethyl- Δ^5 -dihydroronthebainone enol methyl ether and O-isobutyryl-N-cyclopropylmethyl- Δ^5 -dihydroronthebainone enol methyl ether.

EXAMPLE 8

Using N-cyclopentylmethyl- Δ^6 -dihydroronripavine, prepared as in Example 7 of U.S. 3,299,072, in place of N-cyclopropylmethyl- Δ^6 -dihydroronripavine in the procedure of Example 2 gives N-cyclopentylmethyl- Δ^5 -dihydroronripavine enol methyl ether.

A portion of the above prepared product in ethanol is treated with an equimolar amount of hydrobromic acid in ethanol. The resulting solution is treated with benzene, then concentrated in vacuo. Diethyl ether is added. Filtering gives the hydrobromide salt of N-cyclopentylmethyl- Δ^5 -dihydroronripavine enol methyl ether.

Similarly, using N-cyclohexylmethyl- Δ^6 -dihydroronripavine, prepared as in Example 7 of U.S. 3,299,072, N-cyclohexylmethyl- Δ^5 -dihydroronripavine enol methyl ether and the hydrobromide salt thereof are obtained.

EXAMPLE 9

Δ^6 -dihydroronthebaine (4.05 g.), obtained in the manner described in Example 4 of U.S. 3,299,072, is reduced with metallic sodium in liquid ammonia in the manner

described in Example 1 to give Δ^5 -dihydronorthebainone enol methyl ether as colorless rhombic plates, M.P. 210-211° C.

A mixture of Δ^5 -dihydronorthebainone enol methyl ether (3.0 g.) and propargyl chloride (0.75 g.) in 50 ml. of ethanol containing 1.0 g. of sodium bicarbonate is heated at reflux with stirring for 12 hours. The mixture is then concentrated in vacuo. The residue is washed with water and extracted with benzene. The benzene extract is concentrated in vacuo. Adding diethyl ether and filtering gives N-propargyl- Δ^5 -dihydronorthebainone enol methyl ether.

By the same procedure, using the following in place of propargyl chloride:

3,3-dichloroallyl bromide
2,3-dichloroallyl bromide

the products are, respectively:

N-3,3-dichloroallyl- Δ^5 -dihydrothebainone enol methyl ether
N-2,3-dichloroallyl- Δ^5 -dihydrothebainone enol methyl ether.

EXAMPLE 10

N - cyclopropylmethyl - Δ^5 - dihydronororipavinson enol methyl ether (3.4 g.), prepared in the manner described in Example 2, 1.57 g. of nicotinoyl chloride and 20 ml. of dry pyridine are stirred at room temperature for 24 hours. The mixture is then poured into water. Saturated aqueous sodium bicarbonate solution (100 ml.) is added and the resulting mixture is extracted with diethyl ether. The ether extracts are dried with anhydrous magnesium sulfate, filtered and concentrated under reduced pressure. The residue is dissolved in diethyl ether and a solution of salicylic acid in diethyl ether is added. The solid material is filtered off and recrystallized from aqueous ethanol to give 3-O-nicotinoyl-N-cyclopropylmethyl- Δ^5 -dihydronororipavinson enol methyl ether.

Similarly, using an equivalent amount of acetyl chloride in the above procedure, 3-O-acetyl-N-cyclopropylmethyl- Δ^5 -dihydronororipavinson enol methyl ether is obtained.

By the same procedure using propionyl chloride, butyryl chloride, isobutyryl chloride, benzoyl chloride and isonicotinoyl chloride the following products are obtained, respectively:

3-O-propionyl-N-cyclopropylmethyl- Δ^5 -dihydronororipavinson enol methyl ether
3-O-butyryl-N-cyclopropylmethyl- Δ^5 -dihydronororipavinson enol methyl ether
3-O-isobutyryl-N-cyclopropylmethyl- Δ^5 -dihydronororipavinson enol methyl ether
3-O-benzoyl-N-cyclopropylmethyl- Δ^5 -dihydronororipavinson enol methyl ether
3-O-isonicotinoyl-N-cyclopropylmethyl- Δ^5 -dihydronororipavinson enol methyl ether.

A portion of 3-O-nicotinoyl-N-cyclopropylmethyl- Δ^5 -dihydronororipavinson enol methyl ether in diethyl ether is treated with an equimolar amount of hydrogen chloride in methanol at 0° C. to give the corresponding hydrochloride salt.

What is claimed is:

1. A compound of the formula:

and pharmaceutically acceptable acid addition salts thereof, in which:

R1 is

in which R5, R6 and R7 are hydrogen, methyl or halogen; propargyl or cycloalkylmethyl;

R2 is hydrogen, lower alkyl having 1 to 4 carbon atoms, lower alkanoyl, benzoyl, nicotinoyl or isonicotinoyl;

R3 is hydrogen or lower alkanoyl; and

R4 is hydrogen or lower alkyl having 1 to 4 carbon atoms.

2. A compound according to claim 1 in which R1 is cyclopropylmethyl, cyclobutylmethyl, cyclopentylmethyl or cyclohexylmethyl.

3. A compound according to claim 1 in which R1 is allyl, 2,3-dichloroallyl or 3,3-dimethylallyl.

4. A compound according to claim 1 in which R1 is cyclopropylmethyl, cyclobutylmethyl, cyclopentylmethyl, cyclohexylmethyl, allyl, 2,3-dichloroallyl or 3,3-dimethylallyl; R2 is hydrogen or methyl; R3 is hydrogen and R4 is methyl.

5. A compound according to claim 1 in which R1 is cyclopropylmethyl, R2 is methyl, R3 is hydrogen and R4 is methyl, said compound being N - cyclopropylmethyl- Δ^5 - dihydronorthebainone enol methyl ether, and pharmaceutically acceptable acid addition salts thereof.

6. A compound according to claim 1 in which R1 is cyclopropylmethyl, R2 and R3 are hydrogen and R4 is methyl, said compound being N - cyclopropylmethyl- Δ^5 - dihydronororipavinson enol methyl ether, and pharmaceutically acceptable acid addition salts thereof.

7. A compound according to claim 1 in which R1 is cyclobutylmethyl, R2 is methyl, R3 is hydrogen and R4 is methyl, said compound being N - cyclobutylmethyl- Δ^5 - dihydronorthebainone enol methyl ether, and pharmaceutically acceptable acid addition salts thereof.

8. A compound according to claim 1 in which R1 is 3,3 - dimethylallyl, R2 is methyl, R3 is hydrogen and R4 is methyl, said compound being N - 3,3 - dimethylallyl- Δ^5 - dihydronorthebainone enol methyl ether, and pharmaceutically acceptable acid addition salts thereof.

9. A compound according to claim 1 in which R1 is allyl, R2 is methyl, R3 is hydrogen and R4 is methyl, said compound being N - allyl - Δ^5 - dihydronorthebainone enol methyl ether, and pharmaceutically acceptable acid addition salts thereof.

10. A compound of the formula:

in which:

R2 is hydrogen or lower alkyl having 1 to 4 carbon atoms; and

R4 is hydrogen or lower alkyl having 1 to 4 carbon atoms.
